UNITED STATES PATENT OFFICE.

FRANKLIN O. ELLIOTT, OF CATAWBA, NORTH CAROLINA.

THERMOSTAT.

SPECIFICATION forming part of Letters Patent No. 487,519, dated December 6, 1892.

Application filed August 20, 1892. Serial No. 443,644. (No model.)

To all whom it may concern:

Be it known that I, FRANKLIN O. ELLIOTT, a citizen of the United States, residing at Catawba, in the county of Catawba and State 5 of North Carolina, have invented certain new and useful Improvements in Thermostats, of which the following is a specification, reference being had therein to the accompanying drawings.

10 My invention relates to electrically-operated fire-alarms of the class employing a circuit-closer that is maintained in circuit-breaking position by a fusible plug. Upon the melting of the plug when the surrounding 15 temperature reaches a predetermined degree the circuit is closed and an alarm sounded.

My object is to provide a simple, efficient, and inexpensive automatic circuit-closer of this description; and to this end my invention consists in the device having the construction and combination of parts herein-after specified.

In the drawings, Figure 1 is a longitudinal section of my circuit-closer; Fig. 2, a transverse section, and Fig. 3 a detail perspective view of the terminal-carrying piece detached.

Referring to the drawings by letter, A designates a box or casing, oblong in shape and closed on all sides. One end B has attached 30 to its inner face two separated plates, of copper or other good conductor of electricity b and b, to each of which is connected a wire c, that forms part of a circuit, which includes a battery and an alarm mechanism, such as an 35 electric bell. For hotel use I contemplate attaching the wires c c to the ordinary push-button terminals to enable the usual annunciator to be utilized—an expedient not only rendering a separate alarm mechanism unnecessary, but being, also, of great value in indicating by the annunciator the locality of the fire. Such an arrangement, obviously, will 40 not interfere with the use of the button. The plates b thus form the terminals of a circuit

45 that normally is open. To close the circuit and so sound an alarm on the outbreak of a fire, a sliding contact-carrying rod D is employed, which is supported and guided by the other end B' of the casing and a partition a 50 at the longitudinal center thereof. The inner end of the rod carries a copper or other

suitable contact-disk d, that by the inward movement of the rod is adapted to engage both of the terminal plates B B and so close the circuit, and such inward movement is imparted by a coiled spring E, that encircles the rod in the space between the portion a and the casing end B', one end of said spring bearing against the inner side of the latter and the other end engaging a pin that projects 55 beyond the sides of the rod. To hold the rod away from the terminals B B against the stress of the spring, so as to normally keep the circuit open, an opening d' is provided near the outer end of the rod D to receive a 60 pin F to abut against the outside of the casing end B'. This pin is made of some alloy that will melt at a degree of heat not very much higher than the normal temperature of the room or locality where the device is to be used. 65 The outer end of the rod is furnished with a head or knob d' to enable the rod to be readily drawn out the proper extent to permit the putting in place of the fusible plug.

To insure good contact between the contact-disk d and the terminals, the latter are provided with numerous teats or projections for the face of the disk to impinge against, and said disk is insulated from the rod by a disk g, of rubber or other non-conductor, interposed 70 between it and the end of the rod.

The casing end B is detachably connected with the sides of the casing A by means of ribs b' b' on its opposite edges, which slide in grooves formed in the inner sides, but is rigidly attached to the cover-section a' of the casing that extends from the partition a to itself. This construction is adapted to enable the terminals to be first and permanently fixed at 80 the place determined on—say the center of the ceiling of a room—and then the placing in position of the remainder of the device. At any time the remainder of the device may thus be removed without disturbing the terminals and the wires leading therefrom.

The cover-section a' is provided with holes for the passage of screws to secure it in place, and like holes are also provided in the other section of the casing-cover for a like purpose.

It will be seen that those portions of my device which might be injured or impaired by being exposed are perfectly housed by the

casing A, and at the same time the fusible plug which controls its operation is so situated as to be readily affected when the temperature rises to the predetermined point.

5 Of course modifications of the device can be made which will not involve departure from my invention.

I claim—

1. In a thermostat, the combination of an independent end piece B, carrying contact plates and provided with means for independently securing it to a support, a casing A, carrying an automatic spring-actuated rod provided with a contact-plate, and means for independently securing it to a support, the

inner sides of one end of said casing being provided with grooves in which work the edges of end piece B, as and for the purpose described.

2. In a circuit-closer, in combination, the 20 casing made in two separable parts, one of which carries the fixed and the other the movable contact, substantially as described.

In testimony whereof I affix my signature in presence of two witnesses.

FRANKLIN O. ELLIOTT.
